(57) **CLAIM**

The ornamental design for a bed frame as shown and described.

DESCRIPTION

1. Bed frame

1.1: Perspective

1.2: Left

1.3: Right

1.4: Front

1.5: Back

1.6: Top

1.7: Bottom

1.8: Bottom with an emphasis on the right

1.9: Top with an emphasis on the back

1.10: Bottom with an emphasis on the left

1.11: Exploded

This article is a bed frame in which the frame body and furniture members are assembled solely by means of interlocking joints without the use of ball-nuts or screws, resulting in an aesthetically pleasing appearance and a strong bond.
